UNITED STATES PATENT OFFICE

WALDO L. KRAEMER, OF BROOKLYN, NEW YORK, ASSIGNOR TO KEARFOTT ENGINEERING COMPANY, INC., A CORPORATION OF NEW YORK

SHIP'S WINDOW

Application filed July 18, 1931. Serial No. 551,594.

My invention relates to ship constructions and in particular to the construction of windows therefor.

In the construction of ships, the window openings which are provided in the side walls of the ship are in stepped relation in accordance with the rake of the ship. In these openings, windows are fitted, each window having an outer frame which defines the window openings and which extends through the opening provided therefor in the side of the ship. It is desirable to avoid the stepped appearance of the windows from the deck when several windows are seen in perspective. In order to do this the outer frame of the windows are generally constructed with arcuate upper and lower cross members. These upper and lower arcuate cross members avoid the sharp stepped appearance of the windows and serve to provide an optical effect of a gradual and graceful curve. In the ordinary constructions, however, these arcuate upper and lower frame members of the outer frame are visible from the inner side of the ship's wall, particularly so in the unitary ship window construction utilizing a frameless window pane to provide a maximum field of vision.

The arcuate appearance of the upper and lower frame members from the inner side of the ship's wall is extremely undesirable because the rooms are laid out with straight lines and the arcuate frame members of the outer frame of the window, when seen from the interior of the vessel, do not blend with the lines upon which the room is built. To avoid this difficulty, while retaining the advantages of the arcuate upper and lower frame members, is the principal object of my invention.

By my invention I am enabled to secure the advantage of the arcuate cross members of the outer frame and at the same time eliminate the objectionable arcuate appearance from the inner side of the ship's wall. In accordance with my invention, I utilize an offset horizontal member in conjunction with the arcuate cross members of the outer frame. The horizontal cross members are offset inwardly of the arcuate surface of

the outer window frame and are positioned to conceal the arcuate contour of the cross members from the interior of the vessel. Specifically, these horizontal cross members may be integral with the outer frame and offset from the outer surface thereof or they may be on the inner side of the window pane.

Other objects of my invention will appear from the following particular description of the embodiment thereof shown in the accompanying drawings, in which:

Fig. 1 is a perspective of a side wall of a vessel as seen from the deck;

Fig. 2 is a front elevation of a window constructed in accordance with my invention;

Fig. 3 is an enlarged fragmentary section of the same taken on the line 2—2 of Fig. 2;

Fig. 4 is an elevation of a modified form of a unitary window structure constructed in accordance with my invention;

Fig. 5 is an enlarged fragmentary, sectional side elevation of the same; and

Fig. 6 is an enlarged fragmentary, sectional side elevation of another modified form of window.

In Fig. 1, there is shown the side wall of a vessel as it appears from the deck. As is clearly illustrated by Fig. 1, the field of vision of a person standing on the deck may include several windows in the side wall of the vessel. These windows are in stepped relation to each other in accordance with the rake of the vessel. However, by virtue of the curved upper and lower cross members of the window frames, the stepped relation of the windows is not sharply defined and is hardly noticeable. Even on close examination, these windows will appear to gradually vary in elevation in accordance with the arc of a curve rather than in a sharp stepped relation. While this optical effect is desirable, it is equally desirable to avoid the arcuate appearance from the interior of the vessel, which is avoided by the construction which is shown in the remaining figures of the drawings.

The window shown in detail in Figures 2 and 3 of the accompanying drawings is of the unitary type of shelter deck window in

which the entire window structure including the window operating mechanism, is contained in a single unit and in which a frameless window pane is utilized to give the maximum field of vision. As shown, the unitary window structure includes an outer window frame 1 which defines the window opening and an inner frame 2 of substantially twice the length of the window opening, the outer frame being secured to the inner frame. The outer frame member is, in cross section, substantially as shown in Fig. 3, the frame being provided with an outwardly extending circumambient flange 3 and an axial flange 4. The side members 1a of the outer window frame are straight and the upper and lower cross members 1b are arcuate. This outer frame member extends through the window opening in the side wall of the ship and the frame is secured to the side wall by screws 5 extending through the circumambient flange 3. The arcuate upper and lower cross members extend through the window opening and serve to avoid the stepped appearance of the windows from the deck as is clearly illustrated in Fig. 1.

In order to avoid the arcuate appearance of these upper and lower frame members from the interior of the vessel, through the frameless window pane, there are offset portions 1c formed on the frame member which extend across the frame member at the top and bottom thereof. These offset portions are offset inwardly from the outer surface of the outer frame so that they are not clearly defined from the outer side of the ship's side wall and do not enter into the optical effect of the windows. The edges of these offset portions are straight and in elevation the edges are located at the same height as the ends of the arcuate cross members so that the window opening defined by the frame and as seen from the interior of the vessel, is substantially rectangular.

To this frame member, there is secured the inner frame which is substantially L-shape in cross section, having an inwardly extending flange. One side of the flange abuts against and is secured to the inner surface of the axial flange 4 of the outer frame. To this inner frame, there is secured a channeled member 7 which extends across the upper part of the frame and along the sides thereof to a distance substantially below the lower edge of the window opening. This channeled member is filled with a flexible material 8 and constitutes a channel guideway for a frameless window pane 9.

Just immediately below the lower edge of the window opening there is a cross bar 10 extending between the side members of the inner frame. This cross bar supports the window pane traversing means which includes a vertical threaded shaft 11 extending from the cross bar, at the center thereof,

to the lower cross member of the inner frame and being journaled in both the cross bar and the lower cross member of the inner frame. On the upper end of this vertical shaft there is a beveled gear 12 which is secured to the shaft to rotate therewith. Meshing with this gear, there is another gear 13 which is secured to a stub shaft 14 extending through the cross bar transversely thereof and journaled therein. The inner end of the stub shaft is reduced in diameter and extends through the cross bar inwardly thereof. On the extended end of this stub shaft, there is a handle 15 by means of which the stub shaft and the gear 13 are rotated, and through the bevel gear 12 on the screw shaft, the screw shaft is also rotated. On the screw shaft, there is a nut 16 having internal threads complementary to the threads on the screw shaft. This nut has a pair of side flanges extending from diametrical opposite points. Each pair of side flanges includes a lower flange 17 and an upper flange 18 which form substantially a bifurcated extension. The lower flanges of this nut have rounded elevated portions 19 which are adapted to engage the legs of a bifurcated flange 20 of a link 21 secured to the window pane.

The lower edge of the window pane is received in a clamping member which comprises an L-shaped section 22 and a plate 23 which together form a clamp of U-shape in cross section. This clamp fits over the lower edge of the window pane, a padding being placed between the clamp and the glass. To this clamp is secured the link 21, the legs of the bifurcated flange of which extend between the flanges on the nut. The nut is also provided with a projection 24 extending into an opening in the link 21. Thus, as the screw shaft is rotated the nut travels up and down the shaft, depending upon the direction of rotation of the shaft. As the nut travels down the shaft the upper side flanges of the nut engage the bifurcated flange on the link and draw the link downwardly which draws the window pane downwardly. Likewise, when the shaft is rotated so that the nut travels up the shaft the window pane is raised in the guideways.

The lower offset horizontal portion of the outer frame has a beveled inner surface 25. This inner surface cooperates with a jamming member 26 which is secured to the clamping member on the lower edge of the window pane, the jamming member having a surface complementary to the bevel of the lower offset portion of the outer window frame. This jamming member serves to maintain a weathertight connection when the window is in the closed position.

On the inner side of the window there may be a finishing frame 27 having an elevated waist rail 28. The waist rail is elevated so that the upper surface thereof is in the same

plane as the inner edge of the offset portion of the frame member and extends over the cross bar into close proximity to the window pane.

5 It will be seen that the construction described immediately above provides a unitary window structure having a frameless window pane in which the outer frame is provided with arcuate upper and lower cross members for the purpose of eliminating the sharp stepped appearance of the windows from the deck and the offset portion of the frame members present a substantially rectangular window opening effectively concealing the arcuate contour of the cross members of the outer frame from the interior of the vessel. The elevated waist rail also serves to effectively conceal the curved contour of the lower cross member of the outer frame.

20 The window shown in Figs. 4 and 5 differs from that shown in Figs. 2 and 3 principally in that the inner frame is dispensed with. The remaining features of the window are identical with those of the window shown in Figs. 2 and 3. In the construction shown in Figs. 4 and 5, the channel guideway 7 for the window pane is secured directly to the outer frame member which is provided with an integral flange 29 against which the web of 25 the channel guideway abuts, one leg of the channel abutting against the inner surface 30 of the frame and into a recess formed therefor. In this construction in which the inner frame is dispensed with, a stirrup is provided for the screw shaft of the window pane traversing mechanism. The outer frame is extended downwardly at the lower edge thereof and to the sides of the extension is secured the cross bar 10 which supports the window pane traversing mechanism. At the 35 edge of this cross bar and the edge of the extended portion of the frame member there is secured a channel iron which extends downwardly and is inclined to the plane of the screw shaft. This channel member which is substantially triangular in shape and forms a stirrup having inclined sides 31 and a lower cross piece 32 at the lower end thereof in which the lower end of the screw shaft is 40 journaled. In other respects this window is the same as the window shown in Figs. 2 and 3.

45 In Fig. 5 a fragmentary section of a modified form of the window is shown. In this type of window there is no offset portion provided on the outer frame member. The curvature of the lower cross member of the outer frame is effectively concealed by the elevated waist rail 33 of the inner finishing frame 34 and the upper curved cross member is also concealed by the inner finishing frame.

50 It is obvious that various changes may be made in the details of the embodiments shown in the drawings and above particularly described by those skilled in the art

within the principle and scope of my invention as expressed in the appended claims.

Claims:

1. In a ship's construction, a side wall having a series of window openings there-through, the window openings being in stepped relation in accordance with the rake of the ship, a unitary window structure for each of said window openings and including an outer window frame having arcuate upper and lower cross members to avoid a stepped appearance of the windows from the deck, and means for concealing the arcuate cross members of the window frame from the interior of the ship. 70

2. In a ship's construction, a side wall having a series of window openings there-through, the window openings being in stepped relation in accordance with the rake of the ship, a unitary window structure for each of said window openings and including an outer frame having arcuate upper and lower frame members adapted to avoid a stepped appearance of the windows from the deck, and a waist rail offset inwardly from the outer frame member and shielding the arcuate configuration of the lower cross member from the interior of the ship. 85

3. In a ship's construction, a side wall having a series of window openings there-through, the window openings being in stepped relation in accordance with the rake of the ship, a unitary window structure for each of said window openings and including an outer frame having arcuate upper and lower cross members to avoid a stepped appearance of the windows from the deck, and a straight horizontal cross member offset inwardly from the arcuate cross members and concealing the arcuate configuration of a cross member from the interior of the ship. 95

4. In a ship's construction, a side wall having a series of window openings there-through, the window openings being in stepped relation in accordance with the rake of the ship, a unitary window structure for each of said window openings and including an outer frame having arcuate upper and lower cross members to avoid a stepped appearance of the windows from the deck, a window pane, window pane traversing means, and an inner frame member including an elevated waist rail for concealing the arcuate configuration of the lower cross member of the outer frame from the interior of the ship. 100

5. A unitary ship's window comprising an outer frame having arcuate upper and lower cross members adapted to avoid a stepped appearance of windows from the deck of a ship in which the window openings are stepped in accordance with the rake of the ship, an inner frame secured to the outer frame, a window pane slidably mounted between the inner and outer frames, window 115

pane traversing mechanism for raising and lowering the window pane mounted in the inner frame member, and means for concealing the arcuate configuration of the outer frame from the inner side of the window.

6. A unitary ship's window comprising an outer frame having arcuate upper and lower cross members adapted to avoid a stepped appearance of windows from the deck of a ship in which the window openings are stepped in accordance with the rake of the ship, an inner frame secured to the outer frame, a window pane slidably mounted between the inner and outer frames, window pane traversing mechanism for raising and lowering the window pane mounted in the inner frame member, and offset horizontal cross members, offset inwardly from the arcuate cross members of the outer frame and positioned to conceal the arcuate configuration of the outer frame from the inner side of the window.
7. A unitary ship's window comprising an outer frame having arcuate upper and lower cross members adapted to avoid a stepped appearance of windows from the deck of a ship in which the window openings are stepped in accordance with the rake of the ship, an inner frame secured to the outer frame, a window pane slidably mounted between the inner and outer frames, window pane traversing mechanism for raising and lowering the window pane mounted in the inner frame member, and an elevated horizontal waist rail, positioned to conceal the arcuate configuration of the outer frame from the inner side of the window.
8. A unitary ship's window comprising an outer frame having arcuate upper and lower cross members adapted to avoid a stepped appearance of windows from the deck of a ship in which the window openings are stepped in accordance with the rake of the ship, an inner frame secured to the outer frame, a window pane slidably mounted between the inner and outer frames, window pane traversing mechanism for raising and lowering the window pane mounted in the inner frame member, the arcuate cross members of the outer frame having integral horizontal portions offset inwardly from the outermost surface and adapted to conceal the arcuate configuration of the cross members from the inner side of the window.

55. In witness whereof I hereunto subscribe my signature.

WALDO L. KRAEMER.
